UNITED STATES PATENT OFFICE.

EZRA B. SMITH, OF CHICAGO, ILLINOIS, ASSIGNOR TO JOHN EDWARD OGDEN, OF MOUNTAINVILLE, NEW YORK.

AUTOMATICALLY-OPERABLE DOOR-LOCK MECHANISM.

Application filed November 13, 1923. Serial No. 674,445.

This invention relates to door closures for elevator hatchway doors.

As is well known, it is very essential that elevator hatchway doors be closed in case of fire and means has been provided for automatically closing the doors under such circumstances. When the doors are over-counterbalanced or biased to close, this is accomplished by automatically releasing the locking mechanism which holds them in open position. However, after they have been closed unless the operator is present to lock them in closed position, there is a possibility that the supporting chains may melt, thereby again releasing them and permitting them to open.

This invention has for its salient object to provide means for automatically locking hatchway doors in closed position in case of fire.

Further objects of the invention will appear from the following specification taken in connection with the drawings, which form a part of this application, and in which—

Fig. 1 is a sectional elevation of an elevator hatchway illustrating two sets of hatchway doors and the closure and locking mechanism therefor.

Fig. 2 is a vertical sectional elevation broken away and taken at right angles to Fig. 1.

Fig. 3 is a transverse sectional elevation on an enlarged scale taken substantially on line 3—3 of Fig. 1.

Fig. 4 is an enlarged sectional elevation of the structure shown in Fig. 3, and

Fig. 5 is an enlarged view showing the details of the latch for holding the doors in open position.

The invention briefly described consists of locking means such as a pawl normally held in inoperative position but adapted when released to engage the lower door of a pair of door sections and retain the door sections in closed position. The locking means or pawl is in this instance controlled by a weight suspended by a chain and a fusible link. When the link is melted by the heat, the weight falls, automatically releasing the pawl which thereupon moves to operative

position and engages a rack formed on one edge of the lower door section. Further details of the invention will appear from the following description.

In the embodiment of the invention illustrated, there is shown an elevator hatchway 10 and a plurality of sets of hatchway doors A and B mounted in the hatchway and adapted to close the hatchway opening.

Each set of hatchway doors comprises a lower door 11 and an upper door 12. The lower door has arms 13 adjacent its upper edge connected by rods 14 and cables 15 to lugs 16 carried by the upper door section adjacent the lower end thereof. The cables 15 intermediate their ends pass over sheaves 17 mounted in brackets 18 secured to supports 19 in the elevator hatchway. In this particular type of door, the upper section 12 is heavier than the lower section and, therefore, unless the door is latched in open position, the weight of the upper section will automatically close the door.

Since the doors are biased to close, means is provided for latching the doors in open position. This means is particularly illustrated in Fig. 5 and consists of a latch 20 eccentrically pivoted at 21 and normally disposed in inoperative position as shown at the upper end of Fig. 1. A pin 22 positioned in a notch 23 of the latch limits the swinging movement of this latch. The latch 20 is moved to operative position only when the doors are opened and to accomplish this a resilient strip 24 is carried by one edge of the lower section 11 and is adapted to engage the latch as shown at the bottom of Fig. 1 and to move the latch to operative position. When the latch is moved to operative position a pawl 25 carried by the upper end of the latch is positioned over a lug 26 on the edge of the lower section 11 and retains the lower section in open position. A stop lug 27 is fixedly mounted in the hatchway for limiting the downward movement of the section 11.

Means is provided for manually releasing the latch 20 and this means consists of a bell-crank lever 28 to which is connected a cable 29 on the free end of which is mounted

a handle 30 disposed within reach of the operator.

In order to automatically release the latch and to permit the doors to close in case of fire, a weight 35 is mounted in the hatchway and this weight is suspended by a chain 36 from a stud 37. A fusible link 38 is interposed in the chain and in case of fire this link will melt and permit the weight 35 to drop. A stud 39 is positioned in an elongated slot 40 formed in the weight and limits the downward movement of the weight when the weight is released. In order to release the latch 20, a lug 41 is mounted on the weight and is adapted to engage an arm 42 secured to the latch. As the weight drops, therefore, the lug 41 will engage the arm 42 and swing the latch to the position shown at the upper end of Fig. 1, thereby permitting the doors to close.

This locking and releasing mechanism is fully shown and described and claimed in Patent No. 1,482,949, issued to applicant February 5, 1924.

Manually operable means is provided for locking the doors in closed position. This means comprises a disk 50 pivotally mounted on a plate 51 carried by the lower door section 11. This disk has secured thereto an operating handle 52 and has pivoted thereon, at points disposed on opposite sides of the pivot of the disk, arms 53 and 54. These arms are adapted to slide through keepers 55 and when disposed in their outer position as shown in the upper end of Fig. 1, the arms are positioned directly above fixed stops or lugs 56 mounted on the supports 19 in the elevator hatchway. When the disk 51 is swung to its opposite extreme of movement as shown at the bottom of Fig. 1, the arms 53 and 54 will be retracted.

In order to insure the proper positioning of the door sections when they are open and closed, stop means 60 and 61 are mounted respectively on the upper and lower sills 62 and 63. The member 61 is adapted to coact with a hooked member 64 secured to the upper section 12 adjacent the upper end thereof.

The member 60 has oppositely extending flanges 65 and 66 adapted to coact with offset ends 67 and 68 of members 69 and 70 secured respectively to the upper and lower edges of the lower section 11.

When the doors are automatically released from the locks 20 and closed due to the greater weight of the upper door sections, they will be retained in closed position unless the supporting chains are broken or are melted. In order to insure their being held in closed position, there is provided for each set of doors a latching pawl 75 pivoted at 76 to the support 19 and adapted to engage a rack 77 carried by the lower door section

adjacent the lower end thereof. The upper end portion or the latching portion of the pawl is heavier than the offset lower end portion 78 and a spring 79 is also provided for swinging the pawl in an anticlockwise direction. The pawl is normally held in retracted position or out of the path of movement of the rack by reason of the engagement of its offset lower end 78 with the weight 35. When the fusible link 38 is melted and the weight drops, the pawl will be released and will move in an anticlockwise direction, because of its weight and assisted by the pressure of the spring 79, into engagement with the rack 77 thereby supporting the lower door section 11 and retaining the doors in closed position.

The operation of the structure described has already been outlined and, therefore, a further statement of the operation is not deemed necessary.

From the foregoing description it will be seen that means has been provided for automatically releasing the doors from the locking means for retaining them in open position, thereby permitting them to close in case of fire. Furthermore, provision has been made for automatically latching them in closed position, thereby avoiding the possibility of the doors again opening even if their connecting elements break.

Although one specific embodiment of the invention has been particularly shown and described it will be understood that the invention is capable of modification and that changes in the construction and in the arrangement of the various cooperating parts may be made without departing from the spirit or scope of the invention, as expressed in the following claims.

What I claim is:

- Door mechanism comprising a door biased to close and heat controlled means for locking the door in closed position.
- Door mechanism comprising a vertically movable door and heat controlled means for locking the door in closed position.
- Door mechanism comprising a door biased to close and means controlled by a fusible element for locking the door in closed position.
- Door mechanism comprising a vertically movable door and means controlled by a fusible element for locking the door in closed position.
- Door mechanism comprising a door and heat controlled means including a pawl for locking the door in closed position.
- Door mechanism comprising a door and means including a pawl controlled by a fusible element for locking the door in closed position.
- Door mechanism comprising a door, a

- member for locking the door in closed position and heat controlled means for holding said locking member in inoperative position. 65
8. Door mechanism comprising a door, a pawl for locking the door in closed position and heat controlled means for holding said locking pawl in inoperative position. 70
9. Door mechanism comprising a door, a member for locking the door in closed position and heat controlled means, including a weight suspended by a fusible element, for holding said locking pawl in inoperative position. 75
10. Door mechanism comprising a vertically movable door, a member for locking the door in closed position and heat controlled means for holding said locking member in inoperative position. 80
11. Door mechanism comprising a door biased to close, a member for locking the door in closed position and heat controlled means for holding said locking member in inoperative position. 85
12. Door mechanism comprising a vertically movable door biased to close, means to hold the door in open position, normally inoperable means to lock the door in closed position and heat controlled means for releasing said first named means and permitting the operation of said lock means. 90
13. Door mechanism comprising a vertically movable door biased to close, means to hold the door in open position, normally inoperable means to lock the door in closed position and heat controlled means including a weight suspended by a fusible element for releasing said first named means and permitting the operation of said lock means. 95
14. Door mechanism comprising a vertically movable door biased to close, means to hold the door in open position, normally inoperable means including a pawl to lock the door in closed position and heat controlled means for releasing said first named means and permitting the operation of said lock means. 100
15. Door mechanism comprising a door, means including meltable elements for causing the door to close and heat controlled means for locking the door in closed position. 105
16. Door mechanism comprising a vertically movable door, means including meltable elements for causing the door to close and heat controlled means for locking the door in closed position. 110
17. Door mechanism comprising a door, counter-weighting means including meltable elements for causing the door to close and heat controlled means for locking the door in closed position. 115
18. Door mechanism comprising a pair of vertically movable door sections, the upper section being heavier than the lower section, connecting means between the sections whereby the weight of the upper section will close the lower section and heat controlled means engageable with the lower section for locking the door in closed position. 120
19. Door mechanism comprising a pair of vertically movable door sections, the upper section being heavier than the lower section, connecting means between the sections whereby the weight of the upper section will close the lower section and normally inoperative heat controlled means engageable with the lower section for locking the door in closed position. 125
20. Door mechanism comprising a pair of vertically movable door sections, the upper section being heavier than the lower section, connecting means between the sections whereby the weight of the upper section will close the lower section and heat controlled means including a pawl engageable with the lower section for locking the door in closed position. 130
21. Door mechanism comprising a pair of vertically movable door sections, the upper section being heavier than the lower section, connecting means between the sections whereby the weight of the upper section will close the lower section, means for locking the door sections in open position, normally inoperative means for locking said sections in closed position and heat controlled means adapted to coact with both of said locking means. 135
22. Door mechanism comprising a pair of vertically movable door sections, the upper section being heavier than the lower section, connecting means between the sections whereby the weight of the upper section will close the lower section, means for locking the door sections in open position, normally inoperative means for locking said sections in closed position and heat controlled means for releasing said first named locking means and permitting the operation of said second named locking means. 140
23. Door mechanism comprising a door and heat controlled, gravity actuated means for locking the door in closed position. 145
24. Door mechanism comprising a door and heat controlled means including a gravity actuated pawl for locking the door in closed position. 150
25. Door mechanism comprising a door and gravity actuated means controlled by a fusible element for locking the door in closed position. 155
26. Door mechanism comprising a door and heat controlled, spring actuated means engageable with the door for locking the door in closed position. 160
27. Door mechanism comprising a vertically movable door, a gravity actuated mem-

ber for locking the door in closed position and heat controlled means for holding said locking member in inoperative position.

28. Door mechanism comprising a pair of vertically movable door sections, the upper section being heavier than the lower section, connecting means between the sections whereby the weight of the upper section

will close the lower section and heat controlled, gravity actuated means engageable with the lower section for locking the door in closed position.

In witness whereof, I have hereunto set my hand this 29th day of October, 1923.

EZRA B. SMITH.
